UNITED STATES PATENT OFFICE.

ORVILLE Z. FRAZIER, OF ELKHART, INDIANA, ASSIGNOR OF ONE-HALF TO JAMES F. BOYER, OF ELKHART, INDIANA.

INTERNAL-COMBUSTION ENGINE.

1,315,954.

Specification of Letters Patent. Patented Sept. 16, 1919.

Application filed December 22, 1917. Serial No. 208,340.

To all whom it may concern:

Be it known that I, ORVILLE Z. FRAZIER, a citizen of the United States, residing at Elkhart, in the county of Elkhart and State of Indiana, have invented certain new and useful Improvements in Internal-Combustion Engines, of which the following is a specification.

This invention relates to improvements in internal combustion engines, and has reference more particularly to engines of the six-cycle type, although certain features of the invention are applicable with advantage to two-cycle or four-cycle engines. The principal object of the invention is to provide a motor well adapted to utilize as fuel acetylene gas or other combustible gases that are supplied to the working cylinder or cylinders of the engine under considerable pressure. It is well known that acetylene gas, when burned explosively, generates in the cylinder a considerably higher degree of heat than gasoline, kerosene, and fuels of that order; and, in order to maintain the cylinder at a working temperature, it is necessary to provide cooling means other than the usual water jacket. I have accordingly adopted the six-cycle principle in the present invention for the purpose of introducing between the usual exhaust and fuel intake strokes, an intermediate cycle during which air is drawn into and expelled from the cylinder for the double purpose of cooling and scavenging the latter; and the principal object of the invention is to provide a simple and improved three-valve system for introducing the charge, introducing the cooling and scavenging air, and exhausting the air and the burnt charge. Other objects and advantages secured by the invention will be readily understood and appreciated by those skilled in the art from a consideration of the following detail description when taken in connection with the accompanying drawings, wherein I have illustrated a practical and workable embodiment of the invention, and wherein—

Figure 1 is a side elevation, partly broken out and in section, of a four-cylinder six-cycle internal combustion engine embodying my present improvements;

Fig. 2 is a vertical section on the line 2—2 of Fig. 1;

Fig. 3 is a vertical section on the line 3—3 of Fig. 1.

Referring to the drawings, 5 designates an inclosed crank case from which rise four cylinders 6. Extending through the crank case is an engine shaft 7, suitably journaled in the end walls of said crank case and carrying counterweighted cranks 8 connected by pitmen 9 to the pistons or plungers 10, all as usual in engines of this character.

Surmounting the cylinders, and preferably cast integral therewith is a hollow structure that provides a head 11 for each cylinder, cylindrical valve casings 12, 13 and 14, and a water circulation space designated as an entirety by 15 that extends around the valve casings and cylinders. The valve casings 12, 13 and 14 communicate with the upper ends of the cylinders by ports 16, 17 and 18 respectively, and in these valve casings are mounted hollow cylindrical valves 19, 20 and 21 respectively. The valve casings and valves extend transversely of the group of cylinders, and the valves are blanked or closed at one end (the right hand end as shown in Fig. 1), and are formed at the same end with spindles 22, 23 and 24 (Fig. 3) that are journaled in the outer wall 25 of a gear housing located at one end of the casing.

The valve 19 is formed with a series of lateral ports 26, and constitutes the fuel intake valve; these ports being spaced 90 degrees apart around the axis of the valve so as to successively serve the port 16 of the four cylinders. The open end of the valve 19 communicates by a manifold, indicated at 27 in Fig. 1, with a source of fuel supply which preferably consists of an explosive mixture of acetylene gas and air.

The valve 20 is the air intake valve and is provided with a series of lateral ports 28 spaced at 90 degree intervals around its axis, these ports successively serving the ports 17 of the several cylinders to admit scavenging and cooling air, the left hand end of the valve (Fig. 1) being open and preferably equipped with a funnel-shaped end 29 having a strainer 30 thereon.

The valve 21 serves to exhaust both the scavenging air and the burnt charge, and to this end it is provided with two series of ports, 31 and 32, the former serving to ex-

haust the burnt charge and the latter to exhaust the cooling and scavenging air, the ports of each series being grouped 90 degrees around the axis of the valve so as to serve the four cylinders successively. One end of this valve 21 communicates with an exhaust manifold indicated at 33 in Fig. 1.

The three valves are continuously rotated in the same direction from a moving part of the engine. Figs. 1 and 3 illustrate a simple and practical mechanism for actuating these valves from the engine shaft 7. Referring to these views, on the engine shaft is a spur pinion 34, and fast on the spindles 22, 23 and 24 of the valves are spur gears 35, 36 and 37 respectively. The teeth of the gears 35, 36 and 37 on the one hand and the pinion 34 on the other are in a three to one relation, the gears having for instance 51 teeth and 26 the pinion 17 teeth, and around the gears and pinions is trained a sprocket chain 38 preferably provided with a tightener, indicated at 39.

On opposite sides of the crank casing 5 I have indicated lugs 40 by which the engine may be mounted on the side bars or sills of a chassis frame when employed as an automobile motor. When used as a stationary engine these lugs are of course omitted and 30 a suitable base or pedestal provided. At 41 I have indicated a magneto mounted on a bracket 42 and driven from the engine shaft 7 by gears 43 and 44 on the engine and magneto shafts respectively and a connecting 35 belt or chain 45, this magneto drive being housed within a narrow casing at the opposite side of the engine closed by an outer cover plate 46. The magneto shaft indicated at 47 is preferably extended through 40 this casing and forms also the drive shaft of a rotary pump 48 which maintains circulation of water through the water jacket of the engine. The shaft 47 also, in the particular embodiment of the invention here 45 shown, extends beyond the pump 48 and is provided with a bevel pinion 49 driving a cooperating pinion 50 on a countershaft 51, this latter and the extension of the shaft 47 constituting the operating shafts of a ball 50 governed mechanism for actuating a fuel control valve, this mechanism not being herein shown and described, but forming the subject matter of Letters Patent No. 1,280,201, granted to me Oct. 1, 1918.

At 52 I have indicated conventional spark plugs with which each of the cylinders is equipped, and at 53 I have shown the usual fly wheel on the engine shaft 7.

As previously stated, the novel features 60 of this invention reside chiefly in the three hollow rotary valves which serve to admit the charge, admit the cooling and scavenging air, and exhaust the latter and the burnt charge, respectively, and the actuating 65 mechanism of these valves. It will be noted

that no springs are employed, which is especially desirable in an engine employing a high temperature fuel. The action of the valves is absolutely positive in both opening and closing and their movements are 70 fixed and certain and incapable of disarrangement so long as the valves themselves and their actuating means remain intact. The entire construction is compact and adaptable to the limitations of motor vehicle 75 use. Although more particularly designed to use acetylene gas or other high temperature fuel, it is manifestly equally well adapted to use gasolene, kerosene, or illuminating gas, or any of the other known liquid 80 or gaseous fuels generally employed in internal combustion motors.

I claim:

1. In a six-cycle internal combustion engine, the combination with a plurality of cylinders arranged side by side, pistons in said cylinders, and an engine shaft, of three cylindrical valve-casings disposed in parallel relation transversely of said cylinders and each formed with ports communicating with 90 the latter, a tubular fuel supply valve rotatable in one of said casings, a tubular air supply valve rotatable in another of said casings, and a tubular air and fuel exhaust valve rotatable in the third of said casings, 95 each of said valves being formed with lateral ports adapted to register successively with said valve-casing ports, means for continuously rotating said valves simultaneously from said engine shaft, and a water 100 jacket surrounding said valve-casings and cylinders.

2. In a six-cycle internal combustion engine, the combination with a plurality of cylinders arranged side by side, and pistons 105 in said cylinders, of a pair of cylindrical valve-casings disposed in parallel relation on opposite sides of said cylinders, respectively, and in ported communication with the latter, a tubular fuel supply valve rotatable in one 110 of said casings, a tubular air and fuel exhaust valve rotatable in the other of said casings, a cylindrical valve casing disposed between and parallel with said first-named valve casings and in ported communication 115 with said cylinders, and a tubular valve supplying scavenging air rotatable in said last-named casing.

3. In a six-cycle internal combustion engine, the combination with a plurality of cylinders arranged side by side, and pistons in said cylinders, of a pair of cylindrical valve casings disposed in parallel relation on opposite sides of said cylinders, respectively, and in ported communication 125 with the latter, a tubular valve rotatable in one of said casings and formed with a series of lateral ports for admitting fuel to said cylinders successively, a tubular valve rotatable in the other of said casings 130

and formed with two series of lateral ports for discharging scavenging air and products of combustion respectively from said cylinders successively, a cylindrical valve casing disposed opposite the outer ends of said cylinders and between and parallel with said first-named valve casings and in ported communication with said cylinders, and a tubular valve in said last-named casing formed with a series of lateral ports for supplying scavenging air to said cylinders successively. 10

ORVILLE Z. FRAZIER
